(57) **CLAIM**

The ornamental design for a filtered face mask respirator with cap, as shown and described.

DESCRIPTION

The present application claims the benefit of provisional patent application 63/102,253 to Soma et al., titled: “Tactical Armed Forces Filtering Face Mask,” filed Jun. 5, 2020 which is incorporated herein by reference.

The present application is also related to co-pending utility application Ser. No. 16/873,908 titled “Filtered Face Mask” filed the same day.

The present application is additionally related to co-pending design patent application Ser. No. 29/742,298 titled “Filtered Face Mask Respirator” filed on the same day.

The present application is also related to co-pending design applications for “Filtered Face Mask” and “Filtered Face Mask with Cap” application Ser. Nos. 29/742,297 and 29/742,296 respectively both filed on the same day as the present application.

The invention described herein may be manufactured and use by or for the Government of the United States of America for governmental purposes without the payment of any royalties thereon or therefor.

FIG. 1 is an isometric top, right, front view of a first embodiment of a filtered face mask respirator with cap in accordance with the invention;

FIG. 2 is an isometric bottom rear left view thereof;

FIG. 3 is a front view of the embodiment of FIG. 1;

FIG. 4 is a right side view of the embodiment of FIG. 1;

FIG. 5 is a rear view of the embodiment of FIG. 1;

FIG. 6 is a left side view of the embodiment of FIG. 1;

FIG. 7 is a top view of the embodiment of FIG. 1;

FIG. 8 is a bottom view of the embodiment of FIG. 1;

FIG. 9 is a first cross sectional view of the embodiment of FIG. 1 taken at the section line 9-9 of FIG. 3;

FIG. 10 is a second cross sectional view of the embodiment of FIG. 1 taken at the section line 10-10 of FIG. 3;

(Continued)

FIG. 11 is an isometric top, right, front view of a second embodiment of a filtered face mask respirator with cap in accordance with the invention illustrated as a mirror image configuration of the embodiment of FIG. 1;
 FIG. 12 is an isometric bottom rear left view of the embodiment of FIG. 11;
 FIG. 13 is a front view of the embodiment of FIG. 11;
 FIG. 14 is a right side view of the embodiment of FIG. 11;
 FIG. 15 is a rear view of the embodiment of FIG. 11;
 FIG. 16 is a left side view of the embodiment of FIG. 11;
 FIG. 17 is a top view of the embodiment of FIG. 11;
 FIG. 18 is a bottom view of the embodiment of FIG. 11;
 FIG. 19 is a first cross sectional view of the embodiment of FIG. 11 taken at the section line 19-19 of FIG. 13;
 FIG. 20 is a second cross sectional view of the embodiment of FIG. 11 taken at the section line 20-20 of FIG. 13;
 FIG. 21 is an isometric view of the top, right, front of a third embodiment of a filtered face mask respirator with cap in accordance with the invention;
 FIG. 22 is an isometric view of the bottom rear left of the third embodiment of FIG. 21;
 FIG. 23 is an front view of the embodiment of FIG. 21;
 FIG. 24 is a right, side view of the embodiment of FIG. 21;
 FIG. 25 is a rear view of the embodiment of FIG. 21;
 FIG. 26 is a left side view of the embodiment of FIG. 21;
 FIG. 27 is a top view of the embodiment of FIG. 21;
 FIG. 28 is a bottom view of the embodiment of FIG. 21;
 FIG. 29 is a first cross sectional view of the embodiment of FIG. 21 taken at the section line 29-29 of FIG. 23;
 FIG. 30 is a second cross sectional view of the embodiment of FIG. 21 taken at the section line 30-30 of FIG. 23;
 FIG. 31 is an isometric top, right, front view of a fourth embodiment of a filtered face mask respirator with cap in accordance with the invention illustrated as a mirror image configuration of the third embodiment of FIG. 21;
 FIG. 32 is an isometric bottom rear left view of the embodiment of FIG. 31;
 FIG. 33 is a front view of the embodiment of FIG. 31;
 FIG. 34 is a right side view of the embodiment of FIG. 31;
 FIG. 35 is a rear view of the embodiment of FIG. 31;
 FIG. 36 is a left side view of the embodiment of FIG. 31;
 FIG. 37 is a top view of the embodiment of FIG. 31;
 FIG. 38 is a bottom view of the embodiment of FIG. 31;
 FIG. 39 is a first cross sectional view of the embodiment of FIG. 31 taken at the section line 39-39 of FIG. 33; and,
 FIG. 40 is a second cross sectional view of the embodiment of FIG. 31 taken at the section line 40-40 of FIG. 33.
 The ornamental design for a filtered face mask respirator with cap according to the invention is shown in the drawings, and the dashed lines shown in the drawings form no part of the claimed design.
